UNITED STATES PATENT OFFICE.

JOHN E. STONE, OF PAMPA, TEXAS.

BEET-HARVESTER.

1,121,686.

Specification of Letters Patent. Patented Dec. 22, 1914.

Application filed October 31, 1913. Serial No. 798,489.

To all whom it may concern:

Be it known that I, JOHN E. STONE, a citizen of the United States, residing at Pampa, in the county of Gray and State of Texas, have invented new and useful Improvements in Beet-Harvesters, of which the following is a specification.

The invention has for its object to effect improvements in a machine such as illustrated in my co-pending application Serial Number 761,811.

A particular aim is to improve the construction of "grabs", or beet-gripping devices, whereby beets of various sizes will be gripped with equal efficiency, and without liability of damage to an excessive degree.

It is also a purpose to simplify and cheapen the manufacture of the grabs at the same time that their efficiency is increased.

Additional objects and advantages will appear, some of which will be apparent from the following description, and from the drawings, in which,

Figure 1 is a side view of the machine, Fig. 2 is a cross section thereof looking toward the rear, Fig. 3 is a top view, Fig. 4, is a detail of one of the grab units, Fig. 5, is a fragmentary enlarged view showing the relation of the beets to the gripping devices when engaged.

There is illustrated a machine including a wheeled frame 10, on which there is pivotally supported the rocking frame 11 upon which there are parallel sets of orbitally movable grab devices and a horizontal shaft 12 operated by the annular gears 13, by which the grab devices are held in fixed radial relation.

A bracket frame 14 supports the shaft 12 and other elements to be named, and serves at the same time as a brace or truss for the frame 11, being carried by a series of transverse bars 15 by which the elements of the frame 11 are held in proper relation, as will be understood from the drawings without detailed explanation.

The operation of the grabs is dependent upon their engagement with the ground, and engagement thereof with beets and re-

lease of the same are controlled by two annular cam and supporting plates 16, having broad rear portions beginning at their lower sides and terminating just beyond a topping device at the upper part of the machine. 55 Briefly, the grabs consist of two sets of resiliently connected ground-engaging arms 19 and beet engaging arms 18, the latter being opposed, the plates 16 operating between the respective kinds of arms in each 60 set, having narrow portions which allow the grabs to open under the effect of the resilient connections and having wide portions which force the opposed beet-engaging arms toward each other. In my improved construction the number of beet-engaging arms is double that of the ground-engaging points, and the former are connected in pairs with the latter. Thus a unit of the grab devices consists of one ground-engag- 65 ing arm and two beet-engaging arms. The ground-engaging arm is comparatively broad, and consists of a piece of heavy sheet metal having one end pointed, and bent to present two parts at right angles to each other, 70 the ground engaging or pointed end 17 being the longer, the other 20 extending horizontally and being secured to the gear ring 13 by suitable means, one convenient method being by welding, as these parts 75 are of a fixed relation and require to be very rigidly held.

Opposite the gear 13, the horizontal portion 20 is provided with two guides 21, which may be formed integrally with each 85 other. Slidable in these guides 21 there are stems 22 connected pivotally to the inner ends of the beet-engaging arms 18, these stems being comparatively broad so that the arms 18 will be held securely in radial alignment with the ground-engaging arms 19. Centrally of each of the arms 18 and 19 an elongated opening is formed, the metal of the arm at each end of the opening being pressed inwardly in the form of parallel ears 23, the 90 ears on the arms 18 being spaced somewhat farther apart than those on the arms 19. Extended between the ears on each arm there are small shafts carrying peripherally grooved rollers 24, of sufficient width to 95 100

support the grabs by the engagement of their flanges with the plates 16. The rollers in both the plates 18 and 19 are of the same width and in the arms 18 have a certain amount of sliding movement on the supporting shafts. The rollers are set as close within the openings of the plates as possible, so that the transverse dimension of the unit will not be excessive. Inwardly of the plates 16 respective helical springs 25 are engaged between the arms 18 and arms 19 of each unit, whereby the engaging jaws 26 of the arms 18 tend always to move into co-engagement with those opposite, when the broad portions of the plates 16 are engaged between the rollers 24, but may be checked against such engagement by an interposed beet, the breadth of the beet thus determining the spacing of the opposed jaws when engaging. When the narrow parts of the plates 16 are interposed between the rollers, the opposed jaws are caused by the springs to move away from each other to the outer limit of their movement, the inner ends of the arms 18 engaging against the portions 20 of the ground engaging members. The rollers 24 will thus always rest closely against the edges of the plate 16. Carried between the stringers 10' of the frame 10 there are two cross beams 28 spaced longitudinally of the frame 10, between which there is supported a chute 29 having an enlarged upper end disposed rearwardly of the center of the grabs, and projected upwardly close beneath the gears 13, being inclined outwardly to a point beneath the beam 10' on the left side of the machine, its upper end being shaped suitably to catch the tops severed by a topping device A, located centrally thereover.

The topping mechanism consists of a knife-carrying arm 35 pivoted on the shaft 12 and projects rearwardly and upwardly to a point closely adjacent the path of the jaws 26, being provided thereat with a broad plate 37, upon which there is secured a knife 38.

The beets carried by the grabs rise adjacent the rear part of the machine and move forwardly over the knife, by which the tops are cut off, the latter falling to the chute 29, while the beets are carried beyond until the termination of the broad parts of the cam plates are reached. The grabs are opened by the narrowing of the cam at this part sufficiently to pass on each side of the conveyer 51, the released beets being caught in the conveyer and carried forwardly.

The ground engaging arms of the grabs may be provided with extensible members 64 whereby the ground engaging elements may be lengthened if desired.

What is claimed:

1. A grab mechanism for harvesters com-

prising parallel cams, opposed grip members slidably engaged therewith, outer members slidably engaged with the cams, said grip members projecting on each side of the cams, said outer members projecting at least on the side opposite the work engaging ends of the grip members, resilient contractible connections between the grip and outer members at said side, means outwardly of the connections to limit convergent movement of the resiliently connected parts, and means to move said grip and outer members upon the cams.

2. In a grab mechanism for harvesters, a cam, a grab unit including a grab arm having bearing on the cam, a carrying member for the unit, said grab arm having pivotal and lateral sliding connection with the carrying member, resilient means connected to the arm under tension to hold it in bearing on the cam and means to move the unit relatively to the cam.

3. In a grab mechanism for harvesters an orbitally moving supporting body, a cam having a bearing face parallel to the path of the said body, transversely slidale members carried by said body, grab arms pivotally connected to the slidale members, members fixed with respect to said body, and yieldable connections between the last named said members and the grab arms under tension to bear the grab arms upon the cam.

4. A machine of the class described including two orbitally movable series of grab elements, each comprising units, each unit including a ground-engaging arm having an inner portion extended at right angles thereto, an annular member secured to said inner portion of the units in respective series, a concentric annular cam plate spaced outwardly of said gear intermediately of said ground-engaging arm, guide means on the inner portion of the ground-engaging arm, a stem slidale therein, a vegetable gripping arm having its inner end pivotally connected to the stem, anti-friction devices carried by each of said arms and engaging the edges of the cam plate, and resilient means co-engaged between said arms intermediately of the cam plate and inner portion of the ground-engaging arm under tension to contract.

5. A grab unit for a harvester of the class described, comprising a ground-engaging arm stamped from sheet metal having an inner end portion bent at right angles to the outer part, a guide element on the outer side of said inner portion, a broad stem member slidale therein, a vegetable gripping arm pivotally connected at its inner end to the stem, intermediate portions of the metal in each of said arms being pressed inwardly to form supporting ears, a shaft engaged between the ears of each arm, flanged rollers

revoluble on the shafts and aligned for engagement with opposite edges of a supporting plate, and resilient means connected to the arms intermediately of the rollers and inner portion of the first named arm under contractile tension.

5 In testimony whereof I have hereunto set

my hand in presence of two subscribing witnesses.

JOHN E. STONE.
